Inventor

Elbridge G. Turner

United States Patent Office.

ELBRIDGE G. TURNER, OF NEW BEDFORD, MASSACHUSETTS.

Letters Patent No. 92,493, dated July 13, 1869.

IMPROVEMENT IN SIGNAL-LANTERNS.

The Schedule referred to in these Letters Patent and making part of the same.

To all whom it may concern:

Be it known that I, ELBRIDGE G. TURNER, of New Bedford, in the county of Bristol, and State of Massachusetts, have invented a new and improved Mode of Indicating the Locality of Fires; and I do hereby declare that the following is a full and exact description thereof, reference being had to the accompanying drawing, and to the letters of reference marked thereon.

My invention consists of a watchman's pocket-lantern, having a colored light, and provided with hooks and other convenient means for attaching it to houses, trees, &c., all as will be hereinafter more fully set out.

To enable others skilled in the art to make and use my invention, I will proceed to describe its construction and operation.

Figure 1 is a perspective view of the lantern.

Figure 2 is a view of lamp and cap of same.

Fig. 1. A', case of lantern; B', glass; C', sliding eye; D' D', screw-hooks; E' E', sockets for hooks; F', handles.

Fig. 2. G', lamp; H', cap, to be screwed on the top of lamp, when not in use, to prevent the oil from leaking out.

Operation.

The within-described lantern, being constructed

with red glass, oil-lamp, screw-hooks, handles, and eye, by which to hang it to the hook, its operation may be noted.

In case of fire, the watchman, having learned its exact locality, screws into the house, or nearest adjacent tree or post, one of the screw-hooks with which the lantern is supplied, and hangs the lantern thereon by the eye.

If the nearest available post should chance to be iron, the lantern may be attached by a strap, passed through the handles and around the post.

I do not confine my improvement to setting red-glass plates in the sides of the lantern; the whole body of the lantern may be made of red glass, with the exception of the top and bottom.

Claim.

What I claim as my invention, and desire to secure by Letters Patent, is—

The combination of lantern A', red light B', sliding eye C', screw-hooks D' D', sockets E' E', handles F' F', lamp G', and screw-cap H', all operating as and for the purpose set forth.

ELBRIDGE G. TURNER.
